UNITED STATES PATENT OFFICE.

ALVAH C. ROEBUCK, OF CHICAGO, ILLINOIS.

FILM-REELING MECHANISM.

No. 820,441.

Specification of Letters Patent.

Patented May 15, 1906.

Application filed January 3, 1905, Serial No. 239,358.

To all whom it may concern:

Be it known that I, ALVAH C. ROEBUCK, a citizen of the United States of America, and a resident of Chicago, in the county of Cook and State of Illinois, have invented certain new and useful Improvements in Film-Reeling Mechanisms, of which the following is a specification.

This invention relates more especially to the type of kinetoscope apparatus which constitutes the subject-matter of the Roebuck and McMillan patents, Nos. 623,413 and 706,113, dated July 4, 1899, and August 5, 1902, respectively; and the present improvement has for its object to provide a simple, durable, and effective structural formation and combination of parts adapted to afford ease and convenience in unreeling the picture-film from its containing-reel and passing the same through the apparatus in giving a moving-picture exhibition and in the subsequent rewinding of such picture-film upon its containing-reel in readiness for a subsequent exhibition, all as will hereinafter more fully appear.

In the accompanying drawings, Figure 1 is a side elevation illustrating the general arrangement of the present invention. Fig. 2 is a detail sectional elevation at line $x_1 x_2$, Fig. 3 at line $x_3 x_4$, illustrating the pawl-and-ratchet connection between the reel-carrying shaft and its immediate driving-pulley. Fig. 4 is a detail sectional elevation at line $x'_1 x'_2$, Fig. 1, of the operating-handle of the mechanism. Fig. 4 is a transverse sectional elevation at line $x^2 x^2$, Fig. 1, of the film-carrying reel and its operating mechanism. Fig. 5 is a sectional elevation at line $x^3 x^3$, Fig. 4, illustrating the spring-latch for holding the film-reel in place upon its supporting-shaft. Fig. 6 is a detail sectional elevation at line $x^4 x^4$, Fig. 4.

Similar numerals of reference indicate like parts in the several views.

The general arrangement of the kinetoscope parts will be substantially the same as in the prior patents, Nos. 628,413 and 706,113, before referred to and will comprise the usual casing 1, the objective 2, a shaft 3, carrying a rotary shutter, a shaft 4, carrying the film-feeding sprocket-drum, a main driving-shaft connected by gear 5 and pinion 6 with the shutter-shaft 3 and adapted to impart continuous rotation to said shutter in actual use, and a vertical post 7, carrying a laterally-arranged shaft, upon which the film-carrying reel 9 is mounted in a plane above

the kinetoscope-casing 1, as illustrated in Fig. 1.

The first part of the present invention involves a structural combination of parts 60 whereby a rapid and convenient change from a high to low driving speed for the film-carrying reel can be effected during the progress of the film-reeling operation and so that in the initial reeling operation, in which the roll of 65 film is of small diameter, a high speed will prevail, which, as the diameter of such roll becomes sufficiently great as to offer too great a resistance to rapid reeling, can be changed at the will of the operator to a slower 70 and more powerful speed, the same to prevail until the reeling operation is completed.

In such structural combination of parts, 10 and 11 are two gear-wheels of different diameters secured upon the reel-carrying 75 shaft 8 and having a separated relation slightly in excess of the width of face of the gears, as shown.

13 and 14 are two gear-wheels of different diameters secured together in closely-adjacent relation upon a secondary shaft 15, carried, in the manner hereinafter described, in a bracket 16 at the upper end of the reel-supporting post 7, before described. The construction is such that with the gears 10 and 80 13 in mesh and the gears 11 and 14 out of mesh a high-speed revolution will be imparted to the reel-carrying shaft 8, while with the gears 11 and 14 in mesh and the gears 10 and 85 13 out of mesh a low-speed revolution will be 90 imparted to said reel-carrying shaft.

17 is a tubular bearing-sleeve formed on the bracket 16 aforesaid and in which the secondary shaft 15 is adapted to have rotary movement, as well as lengthwise adjustment, 95 to bring one or the other of the aforesaid sets of gears into mesh in attaining the functions just set forth.

18 is a stop pin or screw passing through the sleeve 17 and engaging in an elongated 100 circumferential recess 19 in the shaft 15 to limit the endwise movement of the same.

20 and 21 are circumferential recesses formed at the inner end of the shaft 15 and having a separated relation corresponding to 105 that of the gears 10 and 11, before described.

22 is a transverse spring-bolt sliding in a way formed therefor in the bearing-sleeve 17 and provided with a projecting screw or pin 23, adapted for engagement with one or the other of the aforesaid recesses 20 21 to lock 110 the shaft 15 at its different lengthwise ad-

justments. With the described construction the operator presses upon the exposed end of the bolt 22 to move the point of the screw 23 out of the path of the shaft 15, after which 5 said shaft is free to be adjusted lengthwise, and upon the operator releasing the spring-bolt the same returns to its normal position with the point of the screw 23 in engagement with one or the other recess which may be in 10 its path to lock the shaft against accidental lengthwise movement.

24 is a transverse pin, and 25 a circumferential recess at the outer end of the shaft 15, forming a part of an effective yet readily detachable connection for the detachable operating-handle, as hereinafter more fully set forth.

The film-carrying drum has a sliding fit upon the carrying-shaft 8 and is secured 20 against endwise disengagement therefrom by a spring-latch mechanism, as follows:

26 is a hub or neck arranged centrally upon the outer end head of the film-reel and having a central bore for the passage of the end of 25 the shaft 8 aforesaid, and such bore is formed with a recess at one side for the reception of the lower end of the spring-latch, hereinafter described.

27 is the spring-latch, pivoted to the end 30 head aforesaid and provided with a semicircular portion at its lower end adapted to fit the recess formed therefor in the side of the hub, as above set forth.

28 is a radially-arranged pin or screw in 35 the semicircular lower end of the latch 27, adapted for engagement in a circumferential recess 29 near the end of the shaft 8 to afford a substantial yet readily detachable connection between the parts.

40 30 is the operating-handle, having a tubular extension or sleeve 31 adapted to fit the end of the shaft 15 and provided with longitudinal recesses 32, adapted for engagement with the transverse pin 24 of said shaft.

45 33 is a catch-bolt sliding in the handle 30 and provided at one end with a catch-hook 34, adapted for engagement in the recess 25 of the shaft 15 to lock the handle in operative engagement with said shaft.

50 35 is a spring arranged at one end of the catch-bolt 33 and adapted to force the catch-hook 34 thereof into engagement with the recess 25 of the shaft 15 aforesaid.

36 is a stop-pin engaging in an elongated 55 recess in the catch-bolt 33 to limit the lengthwise movement of the same.

The detachable connection above described between the operating-handle 30 and the shaft 15 permits of a ready removal of 60 said handle when the film-reeling operation is completed and the use of said handle for actuating the operating mechanism of the film-feeding sprocket-drum and the rotary shutter of the kinetoscope, and with a view 65 to the attainment of such dual function the

projecting end of the operating-shaft of the kinetoscope will have a similar formation to that of the shaft 15 aforesaid in order that the one handle may have operative engagement with one or the other of said shafts, as 70 required.

75 37 is a pulley mounted on the reel-shaft 8 and connected thereto by a pawl-and-ratchet connection 38, which admits of a rotation of said shaft independent of said pulley when 75 said shaft is rotated in the film-reeling operation of the driving mechanism heretofore described.

39 is a pulley carried by one of the shafts 80 of the kinetoscope and having a belt connection 40 with the pulley 37, and the arrangement is such that in the normal operation of the kinetoscope the pulley 37 will run idle, while in a reverse operation of the kinetoscope said pulley will impart rotation to the 85 reel 9 to rewind the film, as in prior patent, No. 706,113, before referred to.

41 is a vertically-arranged spindle forming the pivot-pintle for a horizontally-swinging door at the rear end of the kinetoscope-casing 90 1. Such spindle is provided with a hinged operating-lever 42 and with a lateral arm 43, adapted for engagement with the carrying-shaft 4 of the film-feeding sprocket-drum to impart independent adjustment to the same, 95 as set forth in detail in my companion application for Letters Patent filed of even date herewith.

Having thus fully described my said invention, what I claim as new, and desire to secure by Letters Patent, is—

1. In a kinetoscope, the combination of a casing, a bearing-bracket arranged above said casing, a lateral shaft journaled in said bracket and adapted to support the film-carrying reel, a secondary shaft journaled in said bracket, pairs of gears on said shafts, one pair being in separated and the other pair in adjacent relation, means for affording a lengthwise adjustment of one shaft and the 105 gears carried thereby, means for locking said shaft at its adjustment, and means for manually operating the secondary shaft, substantially as set forth.

2. In a kinetoscope, the combination of a 115 casing, a bearing-bracket arranged above the casing, a lateral shaft journaled in said bracket and adapted to support the film-carrying reel, a pair of gears secured in separated relation on said shaft, a secondary shaft 120 arranged for rotary movement and lengthwise adjustment in said bracket, a pair of gears secured in close relation on said shaft, means for locking said shaft at its adjustment, and means for manually operating said shaft, 125 substantially as set forth.

3. In a kinetoscope, the combination of a 130 casing, a bearing-bracket arranged above the casing, a lateral shaft journaled in said bracket and adapted to support the film-car-

- rying reel, a pair of gears secured in separated relation on said shaft, a secondary shaft arranged for rotary movement and lengthwise adjustment in said bracket and having a 5 pair of circumferential recesses in spaced relation, a pair of gears secured in close relation on said shaft, a transversely-moving spring-bolt adapted for alternate engagement in said recesses, and means for manually operating 10 the secondary shaft, substantially as set forth.
4. In a kinetoscope, the combination of a casing, a bearing-bracket arranged above the casing, a lateral shaft journaled in said bracket and adapted to support the film-carrying reel, a pair of gears secured in separated relation on said shaft, a secondary shaft arranged for rotary movement and lengthwise adjustment in said bracket and having a 15 pair of circumferential recesses in spaced relation, a pair of gears secured in close relation on said shaft, a transversely-moving spring-bolt adapted for alternate engagement in said recesses, a stop-pin on the bracket engaging an elongated recess in the secondary shaft to 20 limit the lengthwise movement of the same, and means for manually operating the secondary shaft, substantially as set forth.
5. In a kinetoscope, the combination of a casing, a bearing-bracket arranged above 25 said casing, a lateral shaft journaled in said bracket and provided with a recess at one end, a film-carrying reel arranged on said shaft, and a latch mechanism carried on said reel and 30 comprising a hub secured to the reel and 35
- formed with a side recess, a spring-latch pivoted on said reel and having a semicircular portion at one end adapted to fit the side recess of the hub, and a radial pin carried by the semicircular portion and adapted for lock, 40 ing engagement in the recess of the shaft aforesaid, substantially as set forth.
6. In a kinetoscope, the combination of a shaft adapted for manual actuation and provided with a cross-pin and a recess at one end, 45 an operating-handle having a sleeve portion formed with longitudinal recesses for engaging the cross-pin aforesaid, and a sliding spring-bolt moving in said handle and provided with a catch-hook adapted for engagement 50 in the recess of the shaft, substantially as set forth.
7. In a kinetoscope, the combination of a shaft adapted for manual actuation and provided with a cross-pin and a recess at one end, 55 an operating-handle having a sleeve portion formed with longitudinal recesses engaging the cross-pin aforesaid, a sliding spring-bolt moving in said handle and provided with a catch-hook adapted for engagement in the 60 recess of the shaft and with an elongated recess, and a stop-pin engaging an elongated recess in the spring-bolt to limit the movement of the same, substantially as set forth.

Signed at Chicago, Illinois, this 28th day 65 of December, 1904.

ALVAH C. ROEBUCK.
